UNITED STATES PATENT OFFICE.

HAROLD B. MORRIS, OF GLENDALE, CALIFORNIA.

MANUFACTURE OF CHAIRS.

1,273,521.

Specification of Letters Patent. Patented July 23, 1918.

Application filed August 15, 1916. Serial No. 114,989.

To all whom it may concern:

Be it known that I, HAROLD B. MORRIS, a citizen of the United States, residing at Glendale, in the county of Los Angeles and 5 State of California, have invented certain new and useful Improvements in the Manufacture of Chairs, of which the following is a specification.

This invention relates to the manufacture 10 of chairs, and particularly to chairs made by covering a skeleton frame with rattan, rush, paper and other such fibrous materials. Ordinarily chairs of this kind are made by first constructing a skeleton frame complete 15 and then winding covering material on some parts of the frame while other parts are covered by weaving the material thereon. This operation is slow and expensive.

According to my present invention different 20 parts of the chair frame are covered, bent into shape, quickly assembled, and secured in place in a novel way to produce a complete chair which is strong, firm and most durable.

25 In my application for patent No. 36,036, filed June 24, 1915, I have described a method of covering frame pieces before they are bent, and I have also described and claimed one way in which a complete chair 30 may be made by covering some parts of the frame and assembling the parts, and I have also described a way of applying a previously formed machine-woven fabric to the back frame of the chair. In my application, 35 No. 107,446, filed July 3, 1916, I have described and claimed a method of first covering a frame piece of the chair while the frame piece is warm and soft and then bending it to shape, and in my application No. 40 110,217, filed July 19, 1916, I have described and claimed a method of covering a frame piece with a sleeve of covering material while the frame piece is soft and warm and then bending the covered frame piece to 45 produce the desired shape.

In carrying out my present invention I provide a blank from which to form the marginal frame for the back, seat and front legs of the chair, and I preferably first apply 50 a covering to that part of the frame which will form the top of the back. This is preferably done by steaming or otherwise heating and softening the wood and then slipping a sleeve of covering material 55 thereon.

After the frame piece is covered in the manner above described, it is bent while still warm to form a U-shape preliminary blank for the marginal frame of the back, seat and front legs of the chair. Before the 60 covering is applied, as above described, the frame may be reinforced at the points of bending by metal plates which serve to prevent the wood from splitting or cracking during the bending operation and afterward. The covering material also serves a similar purpose. After the blank is bent to U-shape, it is steamed or otherwise heated and softened and is then bent at different points laterally to give shape to the frame 65 preparatory to the further bending operation. Where the frame is made of a plurality of strips of wood hot glue is applied between the strips which are then dried and then, after being again steamed, may be bent 70 laterally to proper shape. Metal plates may be applied where subsequent bendings are to be made and where the frame is constructed of a plurality of strips not only is hot glue applied between them but the strips 75 may be nailed together at suitable intervals. When in this condition the frame may be steamed and held in clamps which contract it, and then hot glue is applied to the frame while the frame is still soft, and a previously 80 made piece of fabric having tubular marginal pieces is slipped onto the frame and positioned in such manner as to form a covering for the back and seat. When this is done, and while the frame is still soft, the 85 latter is bent suitably to locate the back at the proper angle to the seat and the front legs are located in a similar way.

The seat is then reinforced by suitable braces, the upper and lower ends of the 90 fabric are attached to cross pieces of the frame and also to cross pieces at the front and rear of the seat portion of the chair. A stretcher is applied between the front legs and then the hind legs are secured in place. 100 The hind legs are braced by a suitable stretcher, and if necessary braces are employed to connect the upper portions of the hind legs to the back frame above the plane 105 of the seat. The stretchers and hind legs are covered before they are applied, suitable means being employed for securely fastening these parts to the main frame of the chair. The front legs are covered with glue and then sleeves of covering material are 110

applied thereto. In this way the separate parts may be very quickly made and covered and the covered units may be easily shaped, assembled and attached.

5 In the accompanying drawings:—

Figure 1 is a perspective view of one form of chair made in accordance with my invention, a portion of the seat being broken away in order to show the seat braces.

10 Fig. 2 illustrates a strip of wood which may be employed to form the main frame of the chair and which is reinforced at the points of bending.

Fig. 3 shows a plan of a frame piece for 15 the back, seat and front legs made up of a plurality of strips of wood nailed together.

Fig. 4 shows a section on an enlarged scale on the line 4—4 of Fig. 3.

Fig. 5 is a perspective view of a frame 20 piece showing how it may be covered by a sleeve of covering material.

Fig. 6 is a view of a frame piece with a covering sleeve placed thereon.

Fig. 7 shows the marginal frame piece, 25 with the covering sleeve thereon, bent into U form.

Fig. 8 illustrates the next step in the 30 operation where the marginal frame piece is given preliminary shaping for the back, seat and front legs.

Fig. 9 is a view similar to Fig. 8, but shows how the different strips of wood, of 35 which the marginal frame is composed, are nailed together and how they are reinforced at points where the next bending operation occurs.

Fig. 10 is an edge view of the frame shown in Fig. 9.

Fig. 11 is a detail view, showing how the 40 main frame may be made of a single piece of wood and how the blank may be made thinner at certain parts.

Fig. 12 is a detail view, showing how the 45 main frame may be made in two parts joined together, how the corners at the top of the back may be covered, and how the top cross piece of the back may be covered with a part of the fabric which covers the back frame.

50 Fig. 13 illustrates how the frame, constructed in the manner indicated in Fig. 9, may be bent and clamped preliminarily to receiving the fabric which covers the back and seat of the frame.

55 Fig. 14 is a plan view of a piece of fabric which is employed to cover the seat and back.

Fig. 15 is a view on an enlarged scale and in section of the covering shown in 60 Fig. 14.

Fig. 16 shows how a portion of the main frame is covered.

Fig. 17 is a sectional view of the covering material shown in Fig. 16.

65 Fig. 18 is a detail view on an enlarged

scale and in section illustrating how the upper and lower ends of the covering material are connected with cross pieces of the frame.

Fig. 19 is a detail view, showing how 70 the covering material may be constructed to cover the back.

Fig. 20 is a detail view illustrating how the covering material is applied to the sides of the back frame and also to the top cross 75 piece thereof.

Fig. 21 is a perspective view, showing how the main frame is bent after being covered to form the back seat, and front legs, and how it is braced or reinforced. 80

Fig. 22 is a bottom plan view of the seat portion of the frame, showing its braces.

Fig. 23 shows a cross section on the line 23—23 of Fig. 22.

Fig. 24 shows one of the frame pieces 85 employed in forming a back leg.

Fig. 25 is a view of a modified form of the frame piece for forming a back leg.

Fig. 26 illustrates how a frame piece for a back leg, after being covered, is bent to 90 shape.

Fig. 27 shows how two such frame pieces, after being bent to suitable shape for the back legs, are connected by a stretcher or brace. 95

Fig. 28 illustrates how the different parts of the frame may be conveniently nested and packed for shipping.

Chairs of various shapes and kinds may be made in accordance with my invention. 100

Fig. 1 shows a chair of simple construction which by way of example serves to indicate my improvements. A indicates the seat, B the back, C the front legs and D the back legs. The front legs are braced 105 by a stretcher c and the back legs are braced by a stretcher d. A' indicates braces for the seat frame which are applied in the manner hereinafter described.

The main frame of the chair is made of 110 suitably seasoned wood and constitutes the marginal frame of the back and seat and also provides the front legs for the chair. The frame may be made of a single piece of wood or of a plurality of pieces. When 115 a single piece is employed, as indicated at E in Fig. 2, it should be reinforced as indicated at e by thin metal plates, set in recesses in the wood and secured therein as shown. These plates are located at points 120 where the strip is to be bent and serve to prevent the wood from splitting or cracking and to reinforce or strengthen the wood at these points. When a plurality of strips are used, as shown at E' in Fig. 3, they are 125 glued together, reinforced by metal plates e', as shown, and secured by nails or other such devices between the plates, as indicated at e'', for the purpose of keeping the wood from creeping during the bending opera- 130

tion. In this way the outer portions of the strips are left free to slide on each other during the bending process.

That portion of the frame piece which 5 will form the upper portion of the back is first heated and softened, as by steam, then has hot glue applied thereto and is then covered with a suitable material before the strip is bent. This is preferably done by 10 forming a sleeve F of fibrous material and slipping it onto the heated and softened frame piece, in the manner indicated in Figs. 5 and 6. This method of covering and bending a frame piece is more fully de- 15 scribed and claimed in my application for patent No. 110,217 filed July 19, 1916, above referred to. Instead of employing a sleeve the frame piece may be wrapped with covering material.

20 Fig. 6 shows a frame piece with the covering material F applied and in this condition the frame piece is ready to be bent. This bending operation to form the U-shape blank of the kind shown in Fig. 7 should occur im- 25 mediately after the sleeve is slipped onto the frame piece and while the wood is still soft.

Fig. 7 shows the shape of the frame after the first bending operation, and it will be observed that the covering F extends en- 30 tirely across the top of the frame and also around the corners thereof. In this way those portions of the frame where the bends occur are reinforced not only by the metal plates, (which are concealed in Fig. 7) but 35 also by the covering sleeve and splitting or cracking of the wood is avoided.

By employing a plurality of strips should one of them break the others will usually hold fast and the shape of the frame as a 40 whole is preserved.

In order to give proper shape to the blank shown in Fig. 7, to outline the back, seat and front legs before the final bending operation, it is first bent to assume the con- 45 dition shown in Fig. 8, lateral bends being produced at the points e^4 , e^5 , and at this time also the outer ends of the blank may be trimmed or squared off, as indicated at e^6 . Before bending at the points just indicated 50 the blank E', shown in Fig. 7, is steamed or otherwise heated or softened, care being taken however to heat and soften only the lower portion of the blank, that portion containing the covering F not being heated. Where the blank is made of a plu- 55 rality of strips hot glue should be applied between the strips and the strips should be further secured by means of nails or similar devices e^9 . At the points e^4 , e^5 metal plates 60 e^7 , e^8 are applied, these plates being prefer- ably of thin sheet metal sunk into recesses formed in the blank at the points indicated. These plates are used for the purpose of preventing the wood from cracking or 65 splitting when the blank is next bent.

When the frame is in the condition shown in Fig. 9, that is, after it is bent to the shape there shown and is nailed and has the plates applied, it is next steamed or otherwise heated and softened and is placed 70 in clamps M, shown in Fig. 13. These clamps serve to bend the sides of the frame toward each other, as indicated, the bends occurring at the top of the back portion of the frame, which portion has not been 75 steamed or softened preliminary to being placed in the clamps and is therefore some- what springy so that the sides of the frame are held under tension.

While in the condition shown in Fig. 13 80 the lower portion of the frame may be again steamed or softened if necessary and hot glue is applied to that portion of the frame below the covered top portion.

The next step in the process is to apply 85 the covering for the back and seat. Such a covering is illustrated in Figs. 14 and 15. It consists of a fabric I which may be made of rush, paper or other suitable material in suitable machinery. It is woven on a loom, 90 and it is formed at its longitudinal edges with tubes i of suitable size to receive the main frame of the chair. These tubes constitute the edge warps of the fabric, and as the process of weaving the fabric forms 95 no part of the invention herein claimed, fur- ther description of such method of weaving is here omitted. I would say, however, that the fabric may be produced in a continuous sheet or strip and cut into suitable lengths, 100 each length being suitable to cover the back and seat portions of the chair frame. At its upper end the blank is hemmed at i' and receives a rod i^2 which stiffens it. The lower end of the fabric is in like manner 105 hemmed, as indicated at i^4 , and receives a rod i^2 which stiffens it. The fabric blank is applied to the frame while the latter is held in the clamps M. The side portions of the frame below the covered top thereof is 110 steamed and hot glue is applied and while in this condition the fabric I is connected with the frame by inserting the lower ends of the frame into the tubes i of the fabric and then pulling the fabric onto the frame 115 until it assumes the position shown in Fig. 16. While the wood is still soft the covered frame is taken from the clamps and bent to the shape shown in Fig. 21 and after the frame is set the upper edge of the fabric is 120 secured to a cross piece I' which is secured to the main frame of the chair in any suit- able way. Preferably the fabric is bent over the cross piece I', in the manner indi- 125 cated in Fig. 18, and the hemmed, rein- forced edge is inserted in a groove in the underside of the cross piece and held therein by securing devices i^3 . The lower edge of the fabric is in like manner attached to a cross piece I² of the frame. Cross pieces 130

k, k' are attached to the marginal frame at the front and rear of the seat portions thereof and these assist in supporting the fabric in the manner indicated in Fig. 21. 5 The cross pieces hold the sides of the frame in a spread condition and keep the fabric stretched. The front legs of the blank, while in a soft condition, are covered with hot glue and then covered with previously 10 formed sleeves of covering material, such as those indicated in Fig. 21. The front legs may be strengthened by a brace or stringer *c* which is covered and bent to shape before it is secured to the legs at *c'* 15 and to the seat frame at *c''*.

In order to strengthen the seat I employ braces *A'* which are *U* shape, have tenons *a* entering sockets in the frame *E'* and are secured tightly in place by bolts *a'*. The 20 braces may be applied in any suitable way. Preferably the tenons are first inserted in the sockets, then the inner portions of the braces are brought together and the bolts are attached. These braces may be made of 25 bent wood and they are arched downwardly, as shown in Fig. 23, to allow the seat to bend when being used. When the braces are joined in the manner above indicated they serve to stretch the marginal frame and 30 hold it in such condition as to properly support the seat portion of the fabric and hold it under tension.

The hind legs *D* are formed from pieces or strips *d'* which are covered, as indicated 35 at *d''*. Each strip may be reinforced by a metal plate, as indicated at *d''*, or by a metal sleeve *d''*, as shown in Fig. 25. The plate *d''* is preferably applied in a recess in the strip and the sleeve *d''* may be first split and then 40 applied in an annular groove or recess in the strip. It is understood, of course, that the entire strip is surrounded by covering material. Only a portion of the covering material is shown in Figs. 24 and 25. After 45 being covered the strip is bent to the shape indicated in Fig. 26 to form a hind leg and also an extension *d''* which projects under the seat and is attached to the frame thereof at the points *d''* and *d''*, Fig. 1.

50 A previously covered brace or stretcher *d* connects the hind legs, as indicated in Fig. 1. This stretcher is attached in any suitable way to the hind legs and to the seat frame. I preferably employ strengthening pieces 55 *G* which may connect the hind legs with the back frame just above the plane of the seat, in the manner indicated in Fig. 1.

I may make the frame of a single piece of material, as indicated in Fig. 11, and make 60 that portion of the frame which constitutes the top *g* of the back and the corners *g'* thinner than the remaining portions *g''*, or I may make the main frame of two pieces of material *H*, as indicated in Fig. 12, bend 65 them, as indicated at *h*, and join them, as in-

dicated at *h'*, the strips being first covered at the corners as illustrated at *f*. The covering *I* for the back may be formed with an extension *J* which may be turned over the top piece to cover it and to also assist in holding the back cover in place. Instead of forming the strips *H* separately *I* may first form a *U*-shape blank, then separate this blank into two parts, apply the covering material *f*, and then join the parts at *h'*. 70

As shown in Fig. 19, the back covering *I* is formed with the extension *J* just referred to, and this figure of the drawings shows how the tubes *i* may be split and extended at *j* to facilitate in drawing the fabric onto 80 the frame. This is also indicated in Fig. 14.

By my improvements the process of making a chair is not only simplified but the different parts of the frame are covered more securely than by usual processes. Some 85 parts of the frame may be covered by winding machines and may then be bent to proper shape without danger of breaking or splitting, while other parts may be covered by previously formed sleeves or tubes of covering material which may be quickly applied.

The fabric covering for the back and seat 90 may be machine-made and may be very quickly slipped onto the main frame of the chair and attached thereto by glue previously applied. This results in a great saving in time and expense, as ordinarily a 95 great deal of time is consumed in covering the main frame by the hand-weaving operation.

The covered frame parts of several chairs 100 made in accordance with my invention may be easily shipped for transportation and readily assembled for use.

Referring to Fig. 12 I may use the construction there shown when the fabric covering *I* has sharp bends. The two frame pieces may be inserted separately in the tubular margins of the fabric and then joined at *h'*. The sleeves *f* may be applied in any 105 suitable way.

The different parts of the chair may be 110 very quickly assembled for use. The covered marginal blank, in the form shown in Fig. 21, the covered legs (Fig. 27), and the two braces *G* are the only separate parts 115 of the chair and in assembling these parts the legs are secured at *d''*, *d''* to the marginal frame and the braces *G* are secured to the backs of the legs and to the back frame just 120 above the plane of the seat and the chair is then ready for use.

I claim as my invention:

1. In a chair, the combination of a resilient *U*-shaped blank having bends forming 125 back, seat and front leg portions, and a fabric slidably engaged with the sides of said blank and held taut by the resilience of said blank.

2. In a chair, the combination of a *U*- 130

- shaped blank having bends forming back, seat and front leg portions, the sides of said blank being also laterally deflected to define the outlines of the back, seat and legs, and a correspondingly shaped fabric slidably engaged with the sides of said blank and held taut by the resilience of said blank.
3. In a chair, the combination of a U-shaped blank having bends forming back, seat and front leg portions, the sides of said blank being also laterally deflected to define the outlines of the back, seat and legs, and a correspondingly shaped fabric slidably engaged with the sides of said blank.
- 10 4. In a chair, the combination of a resili-ent U-shaped blank having bends forming

the back and seat portions, and a fabric slidably engaged with the sides of said blank and held taut by the resilience of said blank.

5. In a chair, the combination of a U- shaped blank having bends forming the back and seat portions, the sides of said blank being also laterally deflected to define the outlines of the back and seat, and a correspondingly shaped fabric slidably engaged 25 with the sides of said blank.

In testimony whereof, I have hereunto subscribed my name.

HAROLD B. MORRIS.
